UNITED STATES PATENT OFFICE.

GEORGE H. DUNHAM, OF ORANGE, TEXAS.

COMBINED COMB, BRUSH, AND MIRROR.

1,333,907.

Specification of Letters Patent. Patented Mar. 16, 1920.

Application filed June 30, 1919. Serial No. 307,629.

To all whom it may concern:

Be it known that I, GEORGE H. DUNHAM, a citizen of the United States, residing at Orange, in the county of Orange, State of Texas, have invented certain new and useful Improvements in Combined Combs, Brushes, and Mirrors; and I do hereby declare the following to be a full, clear, and exact description of the invention, such as will enable others skilled in the art to which it appertains to make and use the same.

This invention relates to toilet articles, and more particularly to combination toilet articles, and has for its object to provide a structure which will include, in combination, a comb movably mounted and a brush and a mirror fixedly mounted upon a single handle so that any one of the articles may be used while all are assembled, and so constructed, also, that both the brush and the mirror will be removable from the handle so that the several articles may be used in conjunction with each other.

Another object is to provide a structure so made that the comb, when not in use, may be moved to lie within an inclosure for its protection and to give a more compact arrangement, means being provided for holding the comb normally in position for use while other means are provided for holding the comb out of position for use.

In the drawings:

Figure 1 is a perspective view of the present invention with the several articles assembled, the mirror being shown directed upwardly.

Fig. 2 is a transverse section through the head of the device with the several articles assembled.

Fig. 3 is a plan view of one of the handle and head sections illustrating the comb in its retracted position and showing its extended position in dotted lines, the latched spring being also shown.

Fig. 4 is a longitudinal section through the device with the brush and mirror removed, and showing the comb retracted.

Referring now to the drawings, the present invention includes two sections 5 and 6, each consisting of a handle portion 7 and a head portion 8. The handle portion of each section merges into the corresponding head portion at a swell 9 recessed in its inner face, so that when the two sections are secured together as shown in the drawings, there is a chamber 10 lying between the two

swells 9. One of these swells has an opening 11 formed therethrough for the reception of a releasing button which will be later described.

The head portion 8 of the section 5 is recessed as shown at 12, this recess opening through one edge of the head and designed for the reception of a comb member 13 slideable therewithin. At its ends, this recess 12 has its walls slightly extended producing shoulders 14, and the comb member has lugs 15 at its ends which work in the recess and, contacting with the shoulders, limit the outward movement of the comb.

To hold the comb yieldably projected with its teeth beyond the open edge 16 of the recess 12 a pair of strap springs 17 are provided.

The portion of the head section which surrounds the recess 12 is provided in its longitudinal side, adjacent to one end, with a diagonal slot 18, receiving an end of one of the springs 17 therein, the opposite end of the spring engaging against the inner edge 80 of the comb member 13.

A similar diagonal slot 19 is formed in the rearward or inner edge of the comb member and receives an end of the other spring 17 which bears against the corresponding wall of the recess 12, this arrangement of springs being such that the comb member slides properly within the recess 12 without binding.

To hold the comb retracted against the action of the springs 17, a latch spring 20 is provided. This spring is secured to the inner face of the head portion 8 of the section 6, extending longitudinally thereof and working into and out of a longitudinal groove 21 formed in the head portion to which it is attached, and opening into the chamber 10. The spring 20 projects beyond the end of the groove into the chamber 10 and carries a button 22 extending through the opening 11. When this button is pressed, the spring 20 is moved into the groove 21 and thus lies out of engagement with the comb member 13. When the button is released, however, the spring, by reason of its resiliency, moves to project a portion thereof out of the groove 21 and into a groove 23 formed in the comb member 13. Thus, if the comb when projected under the action of the springs 17, be pressed back into the recess 12, the groove 23 will be brought into position to receive the spring 20 there-

within, and this spring will move into the groove and engage against one side thereof so as to hold the comb against the action of the springs 17. When the finger button 22 is 5 pressed, the comb will be released and will be projected by the springs 17.

Each of the head portions 8 has longitudinal side flanges 24, which are inturned to form guide ways for the edges of the removable articles. Between one pair of these 10 flanges 24 there is slidably engaged a mirror 25, while between the other pair of the flanges there is slidably engaged the back of a brush 26. Both the brush and the mirror 15 may be slid longitudinally from between the flanges. Inward movement of the brush and mirror is limited by the swells 9.

As will be seen from the drawings, the arrangement of the present invention is such 20 that it provides a mirror having a handle which may be used individually; a brush having a handle which may be used individually, and a comb having a handle which may be used individually. Since both the 25 brush and the mirror are removable, however, provision is made for using the three articles in conjunction with each other. In such use, the mirror is of course removed, and held in one hand in position to reflect 30 the face of the user. The brush is held in the other hand and is used by wielding the handle, while the comb, projected from the head sections but remaining attached thereto is also used by wielding the handle which is 35 formed of the two handle portions 7. The brush may however be removed in order to clean it or to use it with one hand after the manner of a military brush, if desired.

Thus there is produced a combination device which accomplishes something more than a convenient arrangement of elements, the specific nature of the articles comprising this invention demanding an arrangement in which any one of them can be used individually or in which they can be separated for use in conjunction with each other.

What is claimed is:

In a toilet article, the combination with a head having a recess opening through one edge and contracted at its mouth to produce shoulders, a handle rigidly connected with one end of the head and having a chamber adjacent the same provided with an opening in one side wall, and a latch spring secured within said recess and extending into said chamber and having a button standing within said opening; of a mirror removably mounted upon one side of the head and facing in one direction, a brush removably mounted upon its other side and facing in the opposite direction, a comb slidably mounted within said recess and having shoulders at the ends of its rear edge and a groove adapted to receive said latch spring when the comb is completely housed, and expansive means within the recess tending to normally project the comb and throw its shoulders into contact with those on the head.

In testimony whereof I affix my signature in the presence of two witnesses.

GEORGE H. DUNHAM.
